UNITED STATES PATENT OFFICE

HERMANN SCHULTZ, OF BERLIN-LANKWITZ, GERMANY

CASTING MOLD FOR ALUMINOTHERMIC RAIL WELDING

Application filed July 2, 1929, Serial No. 375,491, and in Germany July 4, 1928.

The present invention relates to certain improvements in molds for aluminothermic railwelding, which involve enclosing the ends of the rails to be welded in a mold, preheating the railends and the mold by means of a gas flame or other medium and pouring superheated metal into the mold to effect a welded joint or union between the sections.

In aluminothermic railwelding it is essential that the rails to be welded and the mold surrounding the rail ends are uniformly preheated.

To this end the invention comprises the construction of a mold having an especially efficient arrangement of the heating gate and an outlet for the hot gases on the same side of the rails.

The heating gate is directed towards the web of the rails and the outlet for the burned gases is arranged level with the base of the rails. The pouring gate serves also as an outlet for the burned gases. If necessary other outlets can be provided.

The invention is illustrated in the accompanying drawing which is a vertical sectional elevation. A is a rail to be welded, B is the mold enclosing the rail A. C is the pouring gate D is the heating gate and E is an outlet for burned gases.

This arrangement of the inlet D and the outlet E, in conjunction with the pouring gate C and the lateral openings in the upper part of the mold between the side walls of the latter and the side faces of the rail heads, provides four outlets which induce a substantially equal distribution of the heating medium over and against the surfaces of the rail ends and also the inner walls of the mold cavity, thereby effecting a substantially uniform heating of all parts of the enclosed rail ends. In other words, the heating medium impinging the webs of the rails at or about the mid height is deflected in part laterally in both directions and in part passes through the usual gap between the rail ends, the latter portions of said products being deflected by the walls of the mold against the opposing surfaces of the rail ends, so that said medium is distributed in substantially equal proportions from the central point of en-

trance, over the surfaces of the rail ends, and produces substantially uniform heating effects on all parts of the rail ends before said heating medium escapes at the four outlets referred to namely, the outlet duct E, the pouring gate C and the two openings formed between the side faces of the rail heads and the adjacent walls of the mold.

What I claim is:

1. A casting mold for aluminothermic railwelding having a heating gate directed towards the web of the rails and having also an outlet for burned gases on the same side of the rails.

2. Casting mold for aluminothermic railwelding having a heating gate directed towards the web of the rails and having also an outlet for burned gases on the same side of the rails level with the base of the rails.

3. A mold for aluminothermic welding operations having an inlet duct for the pre-heating medium extending from one side of the mold into the mold cavity at or about the mid height of the parts to be welded and an outlet or exhaust duct for the heating medium located in the same mold section and extending from near the bottom of the mold cavity to the lateral face of the mold.

In testimony whereof I affix my signature.

HERMANN SCHULTZ.
